UNITED STATES PATENT OFFICE.

HARVEY BISSELL, OF GRAND RAPIDS, MICHIGAN.

THILL-COUPING.

SPECIFICATION forming part of Letters Patent No. 242,425, dated June 7, 1881.

Application filed March 24, 1881. (No model.)

To all whom it may concern:

Be it known that I, HARVEY BISSELL, a citizen of the United States, residing at Grand Rapids, in the county of Kent and State of Michigan, have invented new and useful Improvements in Thill-Couplings, of which the following is a specification.

This invention relates to improvements in thill and poll couplings, and has for its object 10 to provide an efficient and simple construction of the parts, to permit their convenient connection and disconnection, while preventing their accidental disengagement when connected, and at the same time avoid rattling of the 15 parts and the consequent noise.

The invention is clearly illustrated in the accompanying drawings, in which—

Figure 1 is a perspective view of a clip, yoke, or thill-iron, connected and constructed 20 according to my invention; Fig. 2, perspective views of the parts disconnected, and Fig. 3 a longitudinal vertical sectional view.

The letter A indicates a clip, and B the yoke which connects the ends of the clip beneath 25 the axle, the yoke having apertures through which the screw-threaded ends *a a* of the clip pass, and are confined in position by nuts *b b*.

The yoke B is constructed with two forward-projecting parallel arms, C C', at a sufficient 30 distance from each other to create a rectilinear space, and the ends of the said arms are connected by a cylindrical pin, D, all of which parts are preferably made in a single piece of cast or wrought metal. The arm C' is somewhat 35 thicker than the arm C, in order to act as a stop to limit and determine the position of the thill-iron in connecting it with the yoke, as hereinafter described.

The letter E indicates the thill-iron, to which 40 the thills or shafts are attached by bolts passing through the holes *c*. The rear end of the thill-iron is formed or otherwise provided with an enlarged rounded head, F, having flat vertical and parallel sides *d d*, a cylindrical transverse aperture, G, and a slot, H, opening into the same. The solid portion of the head, from the rear edge of the slot H, is gradually enlarged or thickened around and beneath the transverse aperture G, so that the latter is, in 45 fact, eccentrically arranged in relation to the edges of the head, thereby forming a cam-surface 50

face, I. The slot H extends vertically from the aperture G, or substantially at right angles to the thill-iron. At one side thereof is provided a shoulder, H, and therefore, in order to attach the latter to the yoke of the clip, the thill-iron must be lifted to an upright or nearly upright position to bring the aperture and slot in its head into coincidence respectively with the cylindrical pin D and reduced arm C, 55 when the thill-iron can be passed laterally over the yoke until the shoulder H strikes the enlarged arm C', which acts as a stop or abutment to the further lateral movement of the thill-iron, and indicates that the head F is in 60 coincidence with the rectilinear space between the arms C C'. When the parts are in this position the thill is dropped and the slotted portion H passes around the cylindrical pin and assumes a vertical, or nearly vertical, position. As the slot in the head is of a less 65 width than the diameter of the pin, it manifestly follows that the thill-iron cannot drop from the same, while all lateral movement of the thill-iron is prevented by the arms of the 70 yoke, because a portion of the solid head projects above the said arms.

In order to provide a yielding rest for the thill-iron, and at the same time keep its cylindrical aperture in contact with the pin, and thus 75 avoid rattling of the parts and the consequent disagreeable noise, I provide the flat spring I', which is of peculiar construction. This spring is provided with a rearward extension, *e*, which rests under and is supported 80 by the axle, and it then extends over a shoulder on the yoke, and projects in a curved path under the head of the thill, bearing against the cam-surface I. Where the spring passes over the shoulder of the yoke it is formed with 85 an aperture, *f*, through which one end of the clip A passes. It will thus be seen that the spring is substantially supported and confined in position to act on the thill-iron. In turning the thill from its upright position the cam-surface 90 acts on the spring and places it under tension, thereby effectively performing the functions hereinbefore mentioned.

It will, of course, be evident that, instead of 95 widening the arm C' to act as an abutment or stop to the lateral movement of the thill-iron in connecting the parts, the stop may be formed

by enlarging or flanging the head of the pin at the side where it joins the arm C', and thus provide the same result, viz., a stop or abutment to limit and determine the lateral movement and position of the thill-iron with relation to the arms of the yoke.

Having thus described my invention, what I claim is—

The combination, with the yoke having the cylindrical draft-pin and the thill-iron adapted to pass laterally onto the yoke, and constructed with the head F, having the cam-surface I,

of the spring-plate extending in a curved path beneath the cam-head of the thill, and placed under tension by turning the thill-iron downward to connect the parts, substantially as described.

In testimony whereof I have hereunto set my hand in the presence of two subscribing witnesses.

HARVEY BISSELL.
